CAMILLO SACERDOTI, OF MILAN, ITALY

BOAT APPARATUS FOR LOWERING LIFEBOATS TO THE WATER FROM SHIPS

Application filed November 4, 1931. Serial No. 572,987.

The present invention relates to a boat apparatus for lowering life-boats to the water from ships and particularly to boat davits of the type in which the arms or davits supporting the boat extend laterally from the ship as a result of a slackening of the life-boat suspension ropes.

In a well known system of davits, known as davits of the "quadrant type", the boat supporting arm constituting the davit is normally in its upright inboard position and it is mounted on the davit support or base so as to move automatically to an inclined outboard position rolling along a curved surface or surfaces of the support to extend towards the sea from the ship when the suspension ropes, from which the life-boat hangs, are slackened.

The present invention has for its object a new and improved form of davit of the quadrant type referred to above. One object of the present invention is to render more perfect the davit displacement on the slackening of the ropes during the lowering operation of the life-boat from the ship.

Another object of this invention consists in a device in which the lowering of the life-boat is effected more safely and quickly without shocks or tosses; the lowering being therefore more soft and uniform, particularly at the transition point between the end of the oscillating motion of the davit and the beginning of the descent of the boat.

The device according to the present invention is substantially distinguished in that the arms or davits carrying at their outer end the pulleys on which the suspension ropes of the life-boat run are mounted on the davit support or bases so as to be prevented from disengagement therewith. By means of this engagement the davits are positively guided during their displacements from the lowermost to the uppermost positions, in the first of which the life-boat is safely placed well out from the ship over the sea, while in the second position the centre of gravity of the life-boat lies much further out of alignment with the geometrical centre of rotation of the davit when the davit leaves the upper right position.

According to one feature of this invention in a preferred embodiment, the davits are each provided with a forked end or tail at their lower ends, the two arms of this forked tail being engaged with suitably designed tracks or paths carried by the side girders supporting and embracing said davits.

Among other useful and improved features of the device according to the invention may be noted a special supporting path or track arranged so as to prevent any sliding motion of the davit on the support, whatever the inclination of the plane on which the davit runs may be, whereby davits of reduced length are easily provided with the same surety of automatic lowering.

According to another feature of this invention, between the winch of the apparatus and the pulley on which runs the suspension rope a system of pulley blocks is inserted, said system being adapted to impart a suitably increased number of turns to the centrifugal brake acting on the drum of the winch so as to limit its speed of rotation and consequently the speed of fall of the boat, and adapted also to equalize the effort required in raising of the boat. The forked ends or branches of the davits are each provided with suitable rolls engaged with and running in suitable guide-ways in the support, one of said guide-ways being provided with a projection at its upper end to retain the roll until the boat reaches the uppermost point of its raising movement so as to prevent, up to this moment, any inboard motion of the davit.

The lateral displacements of the davit may be prevented in many ways, for example by providing with suitable projecting edges the rolls engaged into the guide ways referred to, which in this case are shaped as slots, or by providing the supports with side girders embracing the lower portions of the davit so as to guide them, or by bifurcating the lower portion of the davit and locating the bifurcated end astride a projecting plate on the support.

The invention will be more closely described with reference to the annexed drawing in which:

Fig. 1 is a side elevation of one form of my invention.

Fig. 2 is a cross-section on the line A—B of Fig. 1.

Fig. 3 is a cross-section on the line C—D of Fig. 1.

Fig. 4 is a top plan view of the same.

Fig. 5 is a side elevation of a modified form.

Fig. 6 is a cross-section on the line E—F of Fig. 5.

In both the embodiments shown in the drawing, the davits 1 are each provided at their outer end 2 with a pulley 3 in which runs the suspension rope 4 of the life-boat. The davits are each provided with a pulley block 5—6, placed on the davit arm at a suitable distance from the end 2, and acting in conjunction with the pulley block 7—8 mounted on the support 9, said pulley blocks so constituting a system of pulley blocks. The branches 10—11 of the forked end of each davit 1 are provided with rolls 12, 13 engaged with and running in suitable guide-ways or tracks 14, 18 on the support 9. The guide way 14 ends at the lowermost point in a curved seat 15 the radius of which is larger than the radius of the roll 12, the guide way 18 being on the other hand shaped 30 in an angular form with its end turned upwardly and outwardly.

The arm 1 is guided in its displacements by and between the two side girders 16, 17 solid with the base or support 9. In lieu of these two side girders on the base, the davit may be guided and prevented from lateral displacement by shaping the lower portion of the davit as two plates 19, 20 embracing between them another vertical plate 9 solid 40 with the base or support 9, as shown in Figs. 5, 6.

The operation of the illustrated device is the following.

Supposing the life boat lowered on the seat, the raising of the boat is effected by drawing 45 the suspension ropes acting on the end 21 by a suitable lifting winch of any type. The weight of the boat suspended on the other end of the ropes acts on the highest point 2 of the davit urging the roll 12 towards the right (in the drawing) and consequently the roll 13 will remain engaged with the top of the slot 18. When the boat reaches the level of the davit, the suspension 50 hooks of the boat catch on the end 2 of the davit in a manner well known to one skilled in the art. If now the winch continues to operate on the rope 21 the system of pulley blocks 5—6 and 7—8, which until this 55 moment has acted as a mere rope guiding pulley, enters into action and the pulley blocks 5—6 and 7—8 approach each to the other while the davit is obliged to rise.

The roll 12 is drawn towards the left (in 60 the drawing), so permitting the roll 13 to de-

scend along the guide way 18, so that the davit turns and rises coming inboard.

The rope, during these last moments, will be drawn in by a length equal to three times the approach of the blocks constituting the 70 system of pulleys, so making it possible to maintain nearly even the effort for the raising of the boat. It is self evident that instead of the three-fold rope on the double blocks one may provide a system with a larger number 75 of pulleys or a simple pulley.

In order to effect the lowering of the life boat, it is sufficient to slack the suspension ropes 4; all the system will be displaced towards the left reaching the position indicated 80 by full lines in the drawing, and the above shown operation will be repeated in opposite order.

The lowering is effected automatically by the centrifugally braked drum of the winch 85 and, on account of the illustrated device according to the invention, it is possible to effect the lowering of the boat on the sea more quickly and safely without shocks or tosses. In effect the speed of the centrifugal 90 brake is increased in the first moment, during the displacement or inclination of the davit, so that said speed will be nearly equal to the speed of the fall of the boat during the second phase of the operation, the path described by the upper end of the davit being larger than twice the length through which the pulley blocks move. As a consequence of this fact it is possible to obtain a regular and soft 95 lowering.

The guiding slot 18 shaped as an angle with a vertical arm, has for its object to prevent during the raising of the boat the davit from moving towards its upright position until the boat reaches the uppermost end 2 of the davit: in effect during the first phases 100 of the raising of the boat the length of the rope drawn in at 21 is equal to the distance through which the boat is raised and the pulley system does not operate because the force 105 necessary for moving the pulleys is higher than that which the winch exerts on the rope for raising the boat: the pulley system will 110 so act as a simple rope guiding system. When the boat reaches the end of its rise and 115 engages its hooks on the end 2 of the davit, the pulley blocks will act and exert on the davit a triple force sufficient to raise the davit.

It is evident that the practical details of the device illustrated may be varied at will and according to the particular condition of the case, without departing from the scope of the present invention.

What I claim is:

1. In an apparatus for lowering life boats 125 from ships, a base having two guide tracks therein, a davit having at its lower end members engaging said tracks, one of said tracks comprising a substantially horizontal portion and a substantially vertical portion ex- 130

tending upwardly from one end of said horizontal portion.

2. In an apparatus for lowering life boats from ships, a base having two guide tracks therein, said tracks being nearer to the center line of the ship than the other, a davit having at its lower end members engaging said tracks, the inner one of said tracks comprising a substantially horizontal portion and a substantially vertical portion extending upwardly from the inner end of said horizontal portion.

3. In an apparatus for lowering life boats from ships, of the type having davits which are turned by the same ropes which serve to raise and lower the boats, said ropes running on pulleys at the outer ends of the davits, that improvement which comprises a base having therein an outer curved guide convex towards the outside of the ship and an inner curved guide convex to the inside of the ship, said inner curved guide having at its lower end a substantially horizontal portion extending towards the outside of the ship, and members on said davit cooperating with and guided by said guides.

4. In an apparatus as claimed in claim 3, said base comprising two parallel members and a central plate in which at least one of said guides is formed, said davit being between said parallel members and having bifurcations at its lower end on each side of said plate.

5. In an apparatus as claimed in claim 3, said base comprising a single plate in which said guides are formed, and said davit having bifurcations at its lower end on each side of said plate.

In testimony whereof, I affix my signature.
